UNITED STATES PATENT OFFICE.

ALOIS HUML, OF CLEVELAND, OHIO.

DESIGN FOR A HAT-PIN GUARD.

42,604.

Specification for Design.

Patented June 11, 1912.

Application filed January 16, 1912. Serial No. 671,524. Term of patent 7 years.

To all whom it may concern:

Be it known that I, ALOIS HUML, a citizen of the United States, residing at Cleveland, in the county of Cuyahoga and State of Ohio, have invented a new, original, and ornamental Design for Hat-Pin Guards, of which the following is a specification, reference being had to the accompanying drawing, forming a part thereof.

I claim:

The ornamental design for a hat pin guard, as shown.

ALOIS HUML. [L. S.]
